UNITED STATES PATENT OFFICE

2,602,376

VALVE SEAT REFACER FOR SAXOPHONES
AND THE LIKE

Nicholas P. D'Alessandro, East Orange, N. J.

Application December 29, 1949, Serial No. 135,793

4 Claims. (Cl. 90—12.5)

1

This invention relates to tools for refacing or restoring flat valve seats, such as the key seats of saxophones.

The seats for the keys or valves of saxophones and the like become rough, pitted or oxidized and accumulate dirt and other foreign matter on the circular surfaces surrounding the air holes thereby preventing the pads on the keys from accurately and tightly seating thereon so that leakage of air and loss of tonal quality results. Owing to the construction and location of such saxophone valve seats, it is very difficult to clean or reface the same.

It is therefore a prime object of the present invention to provide a tool especially designed for cleaning the faces of saxophone valve seats and for refacing and restoring such valve seats to satisfactory working condition.

It is another object of the present invention to provide such a tool that is easily placed in operative position over any of the valve seats of a saxophone, particularly the lower register keys or valves that are provided with guards which cannot be removed.

Another object of the present invention is to provide a tool of this kind with means for adjusting the tool to fit various sizes of valve seats and with means for properly centering the tool on the valve seat.

Another object of the present invention is to provide a tool of this kind that is simple in construction, economical to manufacture and highly efficient in use.

Other objects and advantages of the invention will be apparent from the description thereof to follow taken in connection with the accompanying drawing in which—

Figure 1 is a top plan view of a valve seat refacing tool embodying my invention.

Figure 2 is a bottom plan view thereof.

Figure 3 is a sectional view on an enlarged scale showing the improved tool in operative position on the valve seat of a saxophone.

Figure 4 is a sectional view taken on the plane of the line 4—4 of Figure 2.

In the drawing, the tool is shown as mounted in operative position on the valve seat 1 of one of the lower register keys or valves of a saxophone 2. Such lower keys are usually protected by guards or arms 3 extending over and across the keys with their ends connected to the saxophone pipe. This member protects the valve parts from being fouled or damaged by contact with the clothing of the player or with the surface of an instrument case or other objects.

2

The valve hole is ordinarily of cylindrical construction with a tapered wall and having its port communicating with the opening in the saxophone pipe. The face or top supporting surface 4 of the valve seat is plane and straight for frictionally seating a disc shaped or flap valve member (not shown) that usually is lined with a pad. It is very important that the valve member pad accurately and squarely on the face of the valve seat otherwise there will be a leak, with consequent loss of tonal quality.

The present invention is concerned with a tool for cleaning off foreign matter that might become encrusted on the face 4 of the valve seat, and for refacing the same and for restoring it to satisfactory working condition. This tool comprises a member shown as a circular or disc-shaped metal plate 5 having its bottom surface planar face formed with diagonal cutting edges 6. A guideway comprising a groove 7 is cut medially across the bottom surface of the plate and mounted loosely in this groove is a spindle 8 having an annular groove 9 formed midway its ends. On one side of the groove 9, the spindle is formed with external right hand screw threads 10, and on the other side with left hand screw threads 11. The diameter of the spindle is greater than the width between the edges of the groove 7 so that it cannot fall out at this point. Encircling each of the right hand and left hand screw threaded portions is a nut member 12, and depending from each nut member and extending outwardly of the groove 7 is a pin 13. A semi-circular pilot plate 14 or gripper is fastened to the outer end of each pin with its body portion disposed in a plane parallel with the plane of the body portion of plate 5. The straight sides of the plate 14 are positioned in opposed face to face relationship.

40 A handle 15 having an internal screw-threaded socket portion 16 at one end is threaded on to one end of the spindle 8 and forms an extension thereof. The opposite end of the handle may be knurled as indicated at 17 to facilitate rotation thereof. Rotation of the handle to the right will cause the spindle 8 to rotate and because of the threaded connection between the nuts and spindle, said nuts will move in opposite directions along the spindle carrying the plate members 14 therealong. A set screw 18 extending through an opening 19 in the center of the upper surface of the plate 5 and into the groove 9 in spindle 8 prevents longitudinal movement of the spindle but permits rotation thereof. The 50 spindle 8 and the pins 13 thus constitute means 55

for moving the gripper or plates 14 along the guideway 9 in opposite directions.

In use, the tool may be grasped by the right hand of the user, for example, and with the bottom surface of the plate 5 placed downwardly, the semi-circular pilot plates 14 are inserted into the port of the valve seat thereby guiding the plate 5 to contacting relationship with the face 4 of the valve seat and properly centering said plate. The handle 15 may then be rotated in the order to move the curved peripheral edges of the plate 14 into intimate but loose contact with the inner surface of the wall of the valve port in order to hold the plate 5 against lateral movement during operations and to hold it at a proper angle to the axis of the port. When the plates are thus properly positioned, downward pressure on the plate 5 may be exerted by the fingers 20 of the left hand of the user as shown in Figure 3 in order to hold the plate in a firm manner and against displacement and to force the knife edges 6 into cutting contact with the foreign matter on the face of the valve seat. While pressure is being exerted downwardly on to the plate 5, the handle is moved around horizontally carrying the plate 5 around with it so that the knife edges 6 cut through and remove the foreign matter encrusted on the face of the valve seat thereby refacing said valve seat and restoring it to satisfactory working condition.

The parts of the tool are readily assembled and disassembled and by adjusting the plates 14, the tool may be made to fit various sizes of valve holes.

Furthermore, the construction of the tool is such that, after the removal of the movable parts of the valve, it may readily be slid under the fixtures, such as the guard 3, usually present over the valve seats on the lower end of a saxophone.

Changes in details of construction might be made without departing from the principle of the invention. Also, and as shown, the side of the plate 5 opposite the cutting edges may be made flat and smooth so as to serve as a straight edge or gauge for determining whether or not the valve seat has been accurately refaced.

What I claim is:

1. A valve seat refacing tool comprising a disc-shaped member having cutting edges upon one surface thereof, said member having a groove therein parallel to and opening to the cutting surface, a spindle rotatably mounted in said groove, said spindle having external right hand screw threads at one end and external left hand screw threads at the other end, a plate for and movable along each of said right hand and left hand threaded sections and externally of the cutting surface of the disc-shaped member for engaging the interior of a valve casing to guide said member to operative relation on a valve seat, means for moving each of said plates by its

threaded section, and a handle connected to one end of said spindle for rotating the same to move the plates and for manipulating the disc-shaped member for cutting the face of the valve seat.

5 2. A valve seat refacer for saxophones and the like including a metallic disc-shaped member having diagonal cutting edges along one surface thereof, said member having a diametrical groove opening into said cutting surface, a spindle rotatably mounted in said groove, said spindle having external right hand screw threads at one end and external left hand screw threads at the other end, a pin extending radially from each of said right hand and left hand threaded section

10 15 and outwardly of the cutting surface, a nut member fastened to the inner end of each pin and operatively connected to the threaded section, a plate fastened to the outer end of each pin, and a handle connected to one end of said spindle for rotating the same whereby said nuts move therealong and carry said plates along with them.

20 3. A valve seat refacer for saxophones and the like including a metallic disc-shaped member having diagonal cutting edges along one surface

25 25 thereof, said member having a diametrical groove opening into said cutting surface, a spindle rotatably mounted in said groove, said spindle having external right hand screw threads at one end and external left hand screw threads at the other end, means for preventing longitudinal movement of said spindle, a nut member threaded to each of said threaded sections, a pin extending radially from each nut member outwardly of the cutting surface of the disc-shaped mem-

30 35 ber, a plate fastened to the outer end of each pin, and an elongated handle connected to one end of said spindle and radiating from the periphery of said disc-shaped member for rotating the spindle and for manipulating the disc-shaped member.

40 4. A valve refacing tool comprising a member provided with a planar face, cutting teeth extending substantially over the entire surface of said face, a guideway built into said face along said cutting teeth medially of said face and extending from one side to the opposite side of said face, opposed grippers, each guided along said guideway for movement in opposite directions, and means extending substantially in the plane of said face and connected to said grippers for creating said movement.
